CHURCH PEW

Joseph Palma, Jr., O N. 487 Willow Road,
Wheaton, Ill. 60187

Filed June 1, 1965, Ser. No. 85,518

Term of patent 14 years

(Cl. D15—8)

The ends and sides of the article not shown are like the ends and sides shown.

The dominant features of my design reside in the portion shown in the full lines.

I claim:

The ornamental design for a church pew, substantially as shown and described.
